(57) **CLAIM**

The ornamental design for a suspension support of a motor scooter, as shown and described.

DESCRIPTION

FIG. 1 is a left, front perspective view of a suspension support of a motor scooter showing our new design;

FIG. 2 is a left, rear perspective view thereof;

FIG. 3 is a right, rear perspective view thereof;

FIG. 4 is a left side elevational view thereof;

FIG. 5 is rear elevation view thereof;

FIG. 6 is a top plan view thereof;

FIG. 7 is an enlarged left, rear perspective view thereof; and,

FIG. 8 is an enlarged rear elevational view thereof.

The broken lines showing the remaining portions of the motor scooter are for the purpose of illustrating environmental structure and form no part of the claimed design. The dot-dash broken lines in FIGS. 2, 4, 5, 6, 7 and 8 which define the bounds of the claimed design form no part thereof.
